UNITED STATES PATENT OFFICE

137,312

DESIGN FOR A MOTOR CAR

Edward Wood, Whitby, Ontario, Canada

Application March 31, 1943, Serial No. 109,879

Term of patent 7 years

To all whom it may concern:

Be it known, that I, Edward Wood, a subject of the King of Great Britain and resident of the town of Whitby, Province of Ontario, in the Dominion of Canada, have invented a new, original, and ornamental Design for a Motor Car, of which the following is a specification, reference being had to the accompanying drawings, forming part thereof.

I claim:

The ornamental design for a motor car, as shown.

EDWARD WOOD.
